(57) CLAIM

The ornamental design for a vertically-aligned golf ball holder, as shown and described.

DESCRIPTION

FIG. 1 is a perspective front view of a vertically-aligned golf ball holder depicted in an in-use state, showing my new design;

FIG. 2 is a perspective front view of a vertically-aligned golf ball holder;

FIG. 3 is a front view thereof;

FIG. 4 is a rear view thereof;

FIG. 5 is a left side view thereof with a right side view being a mirror image;

FIG. 6 is a top view thereof; and,

FIG. 7 is a bottom view thereof.

The broken line showing of golf balls in FIG. 1 is for the purpose of illustrating environmental structure and forms no part of the claimed design.
